(57) **CLAIM**

The ornamental design for a flip book, as shown and described.

DESCRIPTION

FIG. 1 is a front perspective view of a flip book showing the design;

FIG. 2 is a left side view of the flip book shown in FIG. 1; the right side view would be a mirror image of this view;

FIG. 3 is a bottom end view thereof;

FIG. 4 is a top end view thereof;

FIG. 5 is plan view of the top thereof;

FIG. 6 is plan view of the bottom thereof;

FIG. 7 is a view of the flip book shown in FIG. 1 in a fully open position; and,

FIG. 8 is a view of the flip book shown in FIG. 1 in a partially open position.

The broken line showing of the circular images, the word “TEXT” and the dashed lines in FIGS. 7 and 8 is for illustrative purposes only and forms no part of the claimed design.
